(57) CLAIM

The ornamental design for a covered game piece holder, as shown and described.

DESCRIPTION

FIG. 1 is a front perspective view of a covered game piece holder embodying my new design with the cover shown in a closed position;

FIG. 2 is a front perspective view similar to FIG. 1, with the cover shown in a raised position;

FIG. 3 is a front perspective view similar to FIG. 2, and including a plurality of game pieces shown in broken lines for illustrative purposes only and forming no part of the claimed design;

FIG. 4 is a side elevational view of the covered game piece holder as seen from the right of FIG. 1, the opposite side being a mirror image;

FIG. 5 is a side elevation view of the covered game piece holder as seen from the right of FIG. 2, the opposite side being a mirror image;

FIG. 6 is a front elevational view of the covered game piece holder of FIG. 2;

FIG. 7 is a rear elevational view of the covered game piece holder of FIG. 3;

FIG. 8 is a top plan view of the covered game piece holder of FIG. 2; and,

FIG. 9 is a bottom plan view of the covered game piece holder of FIG. 2.
